SURFACE TREATING MACHINE

Ivar Jepson, Oak Park, Ill., assignor to Sunbeam Corporation, Chicago, Ill., a corporation of Illinois

Application March 7, 1956, Serial No. 569,990

4 Claims. (Cl. 51—170)

The present invention relates to surface treating machines, and more particularly to power driven devices or tools adapted to be manipulated over a surface to be treated for sanding, grinding, polishing, buffing, or otherwise treating the same. Since the most common use of such devices is with respect to sanding such surface to be treated, it is usual to refer to such surfacing machines as power sanders, although obviously they can be used for other than sanding operations. In the ensuing description and claims when reference is made to a power sander, it is intended to connote broadly surface treating devices.

In surface treating machines, of which perhaps the most important is a sanding machine, the portable electric sander has become very popular in recent years. There is hardly an adult person today who has not had occasion to use a sander in some form or other for treating a surface whether it be the surface of a piece of furniture or some other project. As a result of the "do-it-yourself" trend, there has been a tremendous increase in the demand for portable electric sanders, and there have been extensively sold on the market several types of these sanders, among which are the purely vibratory sander, the rotary disk type sander, the belt type sander, the orbital sander, and others. Of the four types of sanders specifically mentioned above, the orbital sander has the most general application for all-round work, and the present invention is particularly concerned with an improved orbital sander. An orbital sander is one in which the base plate or shoe supporting the sandpaper or other material for affecting the surface to be treated is caused to move in a positive fashion around the orbit of a circle, and hence the name "orbital sander." Such sanders have been available on the market heretofore, but they have had numerous shortcomings. It would be desirable to provide a portable electric sander or surface treating machine which is capable of withstanding extensive use, such as many hours of continuous use. Moreover, the orbital action of the sander should be steady and balanced with a minimum of vibration. Such a sander should be very light in weight and have perfect balance, so that it is comfortable for the operator to use, particularly when performing such functions as sanding flat work, side walls or ceilings. The control of the motor should be located at a convenient place. The device should require substantially no care other than occasional lubrication.

A surface treating machine such as an electric sander requires simple and readily actuatable means for releasing and securing the sandpaper to the machine. In any particular sanding operation it may be desirable to start the surface treating machine with a coarse sandpaper, followed by a medium and then a fine paper, and this action may be followed by a waxing or polishing operation using the same surface treating machine. Obviously, this requires a mechanism for quickly attaching and releasing sandpaper or other surface treating material, and

2

it would be desirable to provide a locking device which clamps any form of abrasive such as sandpaper tightly thereto regardless of the thickness of the abrasive paper and without the requirement of any tools.

5 In an orbital power sander, it is necessary to convert rotary motion developed by an electric motor or other prime mover to oscillating motion by an eccentric or similar device. The forces transmitted to perform a satisfactory sanding operation are substantial and the 10 means of accomplishing this in prior art arrangements have not been satisfactory to insure long years of trouble-free service. It would be desirable to provide an arrangement in which the forces which are transmitted through pulleys, bearings and the like are transmitted 15 directly so as to cause a minimum of wear.

Accordingly, it is an object of the present invention to provide a new and improved surface treating machine.

It is another object of the present invention to provide a portable electric sander of the orbital type which 20 is light in weight and embodies substantially perfect balance.

It is a further object of the present invention to provide a surface treating machine having the desirable features 25 enumerated above.

It is another object of the present invention to provide a surface treating machine of the type in which a base plate moves through an orbital path in which improved means are provided for transferring the force causing such orbital movement of said base plate.

Still another object of the present invention resides in an electric sander having improved clamping means for permitting quick removal and subsequent reattachment of the abrasive paper, which means will securely hold such paper regardless of the thickness, and which releasing and locking means may be actuated without the use 30 of any tools.

Further objects and advantages of the present invention will become apparent as the following description proceeds, and the features of novelty which characterize the invention will be pointed out with particularity in the claims annexed to and forming a part of this specification.

For a better understanding of the present invention, reference may be had to the accompanying drawings in which:

Fig. 1 is a perspective view of a surface treating machine embodying the present invention;

Fig. 2 is a greatly enlarged side elevational sectional view taken substantially along line 2—2 of Fig. 1, with the sandpaper removed therefrom, but showing certain portions in full lines and certain other portions in section in order more clearly to illustrate the present invention;

Fig. 3 is a sectional view taken on line 3—3 of Fig. 2, assuming that Fig. 2 shows the complete structure except for the sandpaper;

Fig. 4 is a sectional view taken on line 4—4 of Fig. 2, again assuming that Fig. 2 shows the complete structure.

Fig. 5 is a fragmentary sectional view taken on line 5—5 of Fig. 4;

Fig. 6 is a perspective view of the damping pad and stamping bracket shown in section in Fig. 5;

Fig. 7 is a fragmentary sectional view taken on line 7—7 of Fig. 2, assuming that Fig. 2 shows the complete structure; and

Figs. 8, 9 and 10 are schematic, somewhat diagrammatic perspective views, illustrating the method of replacing the sandpaper of the surface treating machine of the present invention.

Briefly, the present invention is concerned with a surface treating machine comprising a vertically disposed motor having its shaft extending into a somewhat rec-

tangular-shaped housing which supports a base shoe through a plurality of resilient columns. The driving mechanism between the motor and the base shoe, which latter is constrained to move through an orbital path relative to the motor housing, is housed within the rectangular-shaped housing. A simple and compact arrangement for transmitting the rotary forces produced by the motor to the shoe through an eccentric arrangement is provided. Additionally, simple means are included for permitting ready clamping of any type of sandpaper and the like to the sanding shoe.

Referring now specifically to the drawings, there is illustrated a portable surface treating machine generally designated by the reference numeral 10. This surface treating machine comprises a base plate 11 which should be actuated in an orbital path so that when a suitable element such as sandpaper or the like is secured thereto, a sanding or other surface treating operation can be accomplished in response to the movement of the base plate about its orbital path. The base plate 11 is secured to a suitable base member 12 by resilient means generally designated as 13 and described in greater detail hereinafter. Secured to the base member 12 is a suitable motor housing 14 within which is contained a suitable prime mover or motor means generally indicated as an electric motor 15. A handle 16 secured to the motor housing 14 permits the operator to manipulate the surface treating machine 10.

Considering more in detail the general construction and operation of the surface treating machine 10, consideration is first given to the base plate or shoe 11, which is the portion of the surface treating machine 10 that is actuated for movement in an orbital path to cause a sanding or other surface treating operation. As best shown in Figs. 2 and 3 of the drawings, the base plate 11 is a rectangular plate formed of relatively heavy sheet metal material of a size to accommodate sandpaper or other surface treating material available on the market. The size of the rectangular sheet will, of course, depend upon the size of the motor which it is desired to use to actuate the same. In a surface treating machine 10 built in accordance with the present invention, the base plate 11 was of the order of between three and four inches in width, and between six and eight inches in length. The particular size of the base plate, however, is unimportant so far as the present invention is concerned.

In order to provide a somewhat resilient cushion or backing for a surface treating element, such as an abrasive coated material, indicated as the sandpaper 17, which is to be secured to the base plate 11, there preferably is secured to the lower side of the base plate 11, as viewed in Fig. 2 of the drawings, a padlike member 18 which may be formed of pressed felt, rubber, or similar resilient material. This pad 18 is of sufficient thickness to provide a resilient backing for any element suitable for engaging the work surface to be treated, whether it be an abrasive coated material or the like. As best shown in Fig. 1 of the drawings, the sandpaper 17 is secured to the base plate 11 in a manner to be described hereinafter, so that the active surface of the sandpaper 17 is disposed downwardly as viewed in Fig. 1, and the other side of the sandpaper 17 rests against the resilient pad 18. The resilient pad 18 may be secured to the base plate 11 in any suitable manner. For example, it may be secured adhesively thereto.

For the purpose of actuating the base plate 11 and the associated element attached thereto for performing a surface treating operation, a bearing housing or bearing mounting means 19 is secured to the base plate 11 on the side opposite the side to which the pad 18 is secured, which essentially comprises a cylindrical member having its lower end welded or otherwise secured to an intermediate portion of the base plate. This bearing housing 19 is adapted to support therein a suitable

10 elongated bearing or needle bearing 21. Preferably, an oil wick 22 and a suitable retainer 23 are provided at the upper end of the bearing housing 19 which is open to insure proper lubrication of the needle bearing 21. In a device built in accordance with the present invention, the bearing housing 19 was of the order of an inch in length, but, obviously, it might have other dimensions. It moreover had a diameter of the order of between an inch and an inch and a half.

15 To permit ready attachment and detachment of the sandpaper or other element to be secured to the base plate 11, the two ends of the base plate 11 are deformed slightly to define a pair of upwardly directed flanges 11a and 11b which act as clamping surfaces against which the material such as sandpaper may be frictionally pressed or clamped to secure the same in position. The clamping surface defined by the element 11b might be considered the forward clamping surface, while the clamping surface defined by the element 11a might be considered the rear clamping surface. Preferably, the flanges 11a and 11b do not extend entirely across the width of the plate 11, the extent preferred being shown best in Fig. 3 of the drawings.

20 Cooperating with the clamping surfaces defined by the elements 11a and 11b are a pair of identical locking arms 25 which might be termed sandpaper locking arms where the surface treating machine 10 is a sander. As illustrated, the locking arms 25 each comprise a U-shaped portion, the bight 25a of which cooperates with the associated one of the flanges 11a or 11b to clamp one end of the surface treating element such as 17 thereto. The legs of the U-shaped portion of each locking arm 25, which between them define the bight portion 25a, terminate in lateral projections 25b and 25c which act as 25 trunnions preferably supported in trunnion supports 11c, which may be formed from tabs integral with the base plate 11. A pair of trunnion supports 11c are provided at each end of the base plate 11. To manipulate the sandpaper locking arm 25, one of the trunnions such as 25b of each locking arm 25 is provided with an extension 25d projecting in a manner generally perpendicular to the axis of the trunnion to define a handle whereby the operator may manipulate the locking arm 25. The end of this handle portion, designated as 25e, is flattened to provide an angularly disposed surface which may readily be grasped by the thumb of the operator to manipulate the same. The base plate 11 is further provided with a pair of hook-shaped tabs 11d and 11e disposed on opposite sides of the base plate 11 adjacent the portions 25d of the locking arms 25 so that these portions may be hooked under the locking tabs 11d or 11e to hold the locking arms in sandpaper clamping relationship. Each of these locking arms 25 is preferably formed of resilient steel wire or the like and is designed so that when moved from the dotted line position shown in Fig. 2 of the drawings to the solid line position by rotation about the trunnions 25c and 25b, the bight of the U-shaped clamping portion 25a engages the associated clamping surface defined by flange 11a or 11b before the arm portion 25d thereof engages the base plate 11. Continued movement of the arm portion 25d of each locking arm, so that it eventually engages the locking tab 11d or 11e, will cause a distortion of the bight 25a of the U-shaped portion to insure proper clamping of any material, regardless of how thin, between this bight portion 25a and the clamping surface on the flange 11a or 11b, as the case may be. In view of the detailed description of the locking arms 25, it will readily be appreciated that an element can be secured to the base plate 11 in a very simple manner.

70 As best shown in Fig. 8 of the drawings, the locking arms 25 may be released by unhooking the corresponding arm portions 25d by first pressing down on these arm portions and then pulling slightly sideways to free the corresponding manipulating arms 25d from the hooked portions such as 11d or 11e. The surface treating ma-

chine can then be placed on its side as indicated in Fig. 9 of the drawings, with the ends of the paper inserted between the flanges 11a and 11b and the corresponding cooperating portions of the associated locking arms 25. When this has been done, the sander or surface treating machine can be set down in the manner indicated in Fig. 10 of the drawings and the clamping means secured in the manner shown in Figs. 1 and 10 of the drawings, whereby the sandpaper such as 17 is securely locked thereto. It will be appreciated that this can be accomplished in a satisfactory manner regardless of the thickness of the sandpaper 17. Furthermore, this can be accomplished without the use of any tools.

For the purpose of supporting the base plate 11 for relative movement with respect to a suitable support, and further for the purpose of housing some of the power transmitting mechanism, the base member 12 is provided, which, in an embodiment built in accordance with the present invention, had a rectangular configuration slightly smaller than the base plate 11. Effectively, the base member 12 is illustrated as an inverted rectangular box completely open at the bottom, with the open end overlying the base plate 11. In order to secure the base plate 11 to the base member 12 in a manner to permit the necessary orbital movement of the base plate 11, there are provided resilient supporting columns 13 which extend between the base plate 11 and the base member 12. As illustrated, four columns 13 are provided, one adjacent each corner of the respective base member 12 and base plate 11. As best shown in Fig. 2 of the drawings, each of the columns 13 is preferably formed of a resilient material, such as a rubber column, to each end of which is secured a threaded member designated specifically as 13a and 13b in Fig. 2 of the drawings. These threaded members 13a and 13b may be shaped as bolts with the heads thereof secured adhesively or molded directly to the ends of the resilient column 13. As illustrated in the drawings, the lower ends of the resilient columns 13 abut against the top of the base plate 11 with the threaded portion of the elements 13b extending through suitable openings defined in the base plate 11. Suitable nuts 28 hold the resilient columns 13 in assembled relationship with the base plate 11. Preferably, the resilient pad 18 is provided with a plurality of recesses 29 to receive therein the threaded ends of the members 13b and the nuts 28 so as in no way to interfere with a sanding operation or other surface treating operation.

To secure the upper ends of the resilient columns 13 to the base member 12, which base member 12 is preferably a die casting of lightweight metal such as aluminum or the like, there are provided a plurality of inserts 31 press fitted into suitable openings in the top wall of the base member 12. These inserts are provided with tapped openings to receive the threaded portions of the members 13a. Obviously, the upper ends of the resilient columns 13 are first secured to the base member 12, whereupon the lower ends 13b may then be secured to the base plate 11 in an obvious manner. With this arrangement the base plate 11 is secured to the base member 12 through the resilient columns 13 which will permit limited relative movement between the base member 12 and the base plate 11 to the extent required for orbital movement to perform a satisfactory surface treating operation. In a device built in accordance with the present invention, the resilient columns 13 had a length of between one and two inches, and had a diameter of between one half and three quarters of an inch.

The base member 12 and the motor housing 14 referred to above are effectively a unitary structure insofar as the operation of the device is concerned. However, for assembly purposes, they are separate elements and the housing 14 is preferably also a die casting of lightweight metal such as aluminum. For the purpose of uniting the motor housing 14 and the base member 12

to form a rigid structure, the top of the base member 12 is preferably provided with a plurality of spacer projections 34, best shown in Figs. 2 and 4 of the drawings, which are adapted to engage the lower end of the motor housing 14 at the four corners thereof, thereby to space the motor housing slightly from the base member 12 and provide air passageways such as 35 between the motor housing 14 and the base member 12, and moreover between the spacer members 34.

For the purpose of accurately positioning the motor housing 14, which is of generally rectangular configuration at the lower end thereof, with respect to the base member 12, each of the spacers 34 is provided with a pair of projections 34a. With this arrangement, two of these projections 34a engage the inside of each of the four wall surfaces defining the motor housing 14. Thus, the spacer members 34 properly orientate the motor housing 14 and the base member 12 with respect to the vertical direction, and the projections 34a properly orientate these members 12 and 14 with respect to the horizontal plane when the surface treating device 10 is in the position shown in Fig. 2 of the drawings. For the purpose of securing the motor housing 14 to the base member 12, the former is provided interiorly with a plurality of spaced vertically extending ribs 14a integrally joined to the interior of the housing 14, which ribs have spaced openings 36 at the lower ends thereof to receive fastening means 37 which extend through the top wall of the base member 12.

For the purpose of accommodating a prime mover specifically designated as an electric motor 15, means are provided to hold the field structure of such a motor designated as 38 in assembled relationship with the housing 14 which defines therein the motor chamber 40. The armature 41 of the motor is provided with the conventional armature shaft 42, one end of which is journaled in a bearing 43 suitably supported in one end of the housing 14 which is indicated as a substantially closed end. The other end of the motor shaft 42 is journaled in a bearing 44 supported in the base member 12 which is provided with a suitable opening to permit the lower end of the shaft 42 to extend into a mechanism chamber 44 defined within the base member 12 above the base plate 11 when the device is positioned in the manner shown in Fig. 2 of the drawings.

To insure cooling of the motor 15, there is preferably provided a fan 46 secured to the motor shaft 42 at the lower end of the motor chamber 40 above the base member 12. A suitable fan shroud 47 surrounds the fan 46 and is preferably held in assembled relationship with the base member 12 and the motor housing 14 by the fastening means 37, which may extend through notches or openings defined in the shroud 47. To preclude the drawing of sanding dust into the motor housing 14, preferably the upper end of the housing, as best shown in Fig. 1 of the drawings, is provided with a plurality of air inlet openings 49 whereby the fan 46 may cause the air to flow through the chamber 40 to cool the motor 15 and out through the passageways 35. If desired, the top of the base member 12 immediately beneath the motor housing 14 may also be provided with a plurality of openings (not shown) for the flow of motor cooling air. This air flow will tend to blow the sanding dust away from the motor housing 14.

In order to lubricate the bearing 43, the motor housing 14 is provided with an oil passageway 51 through which oil may be supplied to the bearing 43. To insure lubrication of the bearing 44, the upper surface of the base member 12 is preferably provided with a recess 52 for receiving a suitable oil wick 53. The oil wick 53 is held in position by a suitable combined bearing and oil wick retainer 54 secured to base member 12 by fastening means 55. Thus, retainer 54 holds the bearing 44 assembled to the base member 12, so that when the fastening means 37 are removed, the motor armature 41 remains assembled with the base member 12, and the motor shaft 42 pulls free of the bearing 43, which bear-

ing is held in position in the motor housing 14 by a suitable bearing retainer member 56 held in position by fastening means not shown secured to motor housing 14 and similar to the fastening means 55.

To cause the base plate 11 to move in an orbital path in response to rotation of the armature shaft 42, there is secured to the lower end of the armature shaft 42 within mechanism chamber 44 a toothed pulley 57 for accommodating the conventional endless belt 58 having suitable projections on the inner pulley engaging surfaces thereof. Such driving belts are commonly referred to as timing belts and are capable of transmitting a substantial force, without slippage, between a driving and a driven pulley. The toothed pulley 57 is, of course, the driving pulley.

In accordance with the present invention, a combined driven pulley and counterweight mechanism 59 is provided which has secured thereto by fastening means 60 a sleevelike bearing housing 61. The portion of the combined element 59 exclusive of the counterweight is designated as 59a, while the counterweight portion is designated as 59b. The portion 59a and the bearing housing 61 secured thereto might be termed a rotatable drive member which has defined therein an opening 62 which is so disposed with respect to the combined pulley and counterweight 59 that the exterior of the sleevelike bearing housing is eccentrically disposed with respect to the axis of rotation. The opening or recess 62 might be termed a first recess opening on both faces of the drive member and centered relative to the pulley portion 59a or, in other words, centered relative to the periphery of the drive member. The combined pulley and counterweight 59 is journaled for rotation about a stationary bearing shaft, bearing mounting means or stub shaft 63 suitably supported from the base member 12 so as to depend into the mechanism chamber 44. The bearing housing 61 houses a pair of needle bearing units 64 and 65 which together define elongated bearing means. Moreover, the eccentrically disposed exterior surface of the bearing housing 61 is caused to move in an orbital path and is adapted to be received within the bearing housing 19 secured to the base plate 11, and effectively is journaled within the needle bearings 21 contained therein. As was mentioned above, the pulley portion of the combined pulley and counterweight mechanism 59 is designated at 59a and comprises teeth to cooperate with the toothed belt 58. Actually, a substantial speed reduction is obtained by virtue of the belt and pulley arrangement described above, since the pulley portion 59a is substantially larger in diameter than is the toothed pulley 57. The counterweight portion 59b of the combined pulley and counterweight 59 balances the unbalanced forces produced by virtue of eccentricity of the bearing housing having the opening 62 therein as well as the unbalanced forces created by virtue of the base plate 11.

In accordance with the present invention, the unit comprising the combined pulley and counterweight 59 and the bearing housing 61 secured thereto by the fastening means 60 are arranged to define, on the underside thereof as viewed in Figs. 2 and 3 of the drawings, a central annular recess 67 eccentric with respect to the recess 62 but overlapping this recess 62 for receiving therein the bearing housing 19 secured to the base plate 11. A substantial amount of force is transmitted radially between the telescoped bearing housings 61 and 19 through the needle bearings 21. With the present arrangement, these forces are transmitted directly across the bearings unlike prior art devices where the driving forces are applied to one end of a long shaft and then transmitted to the driven member through the other end of the shaft. With the present arrangement not only is a compact structure provided, but the forces are transmitted in a direct manner with a minimum of vibration. The counterweight portion 59b is effectively disposed to trans-

mit its force radially along a line substantially at the center of the telescoped members 19 and 61.

To insure proper lubrication of the needle bearings 64 and 65, the stationary shaft 63 is preferably provided therein with an axial oil passageway 70a connected to a radial passageway 70b clearly shown in Figs. 2 and 3 of the drawings. A suitable removable cover 71 normally closes the upper end of the axial passageway 70a. Any suitable means for securing the bearing shaft 63 to the base member 12 may be employed. As illustrated, the bearing shaft 63 is in the form of a shouldered bolt having a head 63a at the lower end thereof to hold the combined pulley and counterweight 59 and associated bearing housing 61 assembled thereto. The upper end of the bearing shaft 63 is of reduced cross section and threaded to extend through an opening 72 in base member 12 and secured thereto by a nut 73. It will be apparent that rotation of the motor shaft 42 will cause the base plate 11 to move in an orbital path. In a device built in accordance with the present invention, such movement was an eccentric movement between a quarter inch and a half inch.

So that the operator may readily manipulate the surface treating machine 10, the motor housing 14 preferably includes an integral extension 14b which, together with a removable cooperating handle member 16a, defines the handle 16. The removable handle member 16a is secured to the extension 14b by suitable fastening means such as 74, and is removable to permit access to the electrical control circuit disposed within a hollow recess or chamber designated as 75, defined within the handle portion. This recess is adapted to accommodate a suitable switch 76 connected in the motor circuit in the conventional manner. For the purpose of supporting the switch 76, it preferably is provided with a mounting plate 77, which plate is adapted to be received within cooperating grooves 78 and 79 defined in the handle portions 14b and 16a respectively. Thus, it is merely necessary to position the switch 76 within the recess 75 so that one edge of the plate 77 is disposed within the groove 78 in extension 14b. The handle member 16a is then assembled so that the opposite edge of switch plate 77 is disposed in groove 79. Effectively the grooves 78 and 79 are defined in the edges of an opening 80 provided in the handle 16, one half of the opening being defined in each handle portion 14b and 16a. This opening 80, which is at the upper portion of the handle adjacent the motor housing 14 and adjacent the normal place where the operator will keep his thumb, permits a manually actuatable switch knob 81 to extend outside the handle 16 so that it can readily be actuated by the operator. Preferably, the switch plate 77 includes suitable indicia on the upper surface, as viewed in Fig. 2, which indicates the operating condition of the switch 76. The manually actuatable switch knob 81 may be constructed so as to obscure the indicia which does not properly describe the particular operating condition of the switch 76.

In order to supply the necessary electrical energy for the motor 15, the surface treating device 10 is provided with the conventional power cord 82, which preferably extends into the chamber 75 in the handle 16 through an opening 83. A conventional cord sleeve 84 preferably surrounds the power cord 82 at the entrance opening 83 and includes an enlargement 84a which is adapted to be received within a suitable recess 85 defined in the handle 16. The sizes of the recess 85 and the enlargement 84a are such as to insure that the cord sleeve 84 is clamped into tightly gripping relationship with the power cord 82 when the removable handle portion 16a is secured to the handle portion 14b by the fastening means 74. This, then, affords a suitable strain relief.

To permit two-hand operation, the surface treating device 10 includes a knob 86 secured as by a screw 87 to the upper front of the motor housing 14. Preferably, the

knob 86 is formed of a suitable molded material and may be molded directly to the screw 87. This knob may readily be removed from the surface treating machine 10 when sanding in close quarters, such as corners or the like, and may easily be attached to the sander to permit more satisfactory operation.

In view of the detailed description included above, the operation of the surface treating machine of the present invention, which is particularly well adapted for use as a portable power sander, will readily be understood by those skilled in the art. When power is supplied to the motor 15 upon sliding the switch knob 81 of switch 76 to the on position, rotation of the combined pulley and counterweight 59 occurs, thus causing the eccentric bearing housing 61 to rotate about the bearing shaft 63. Such eccentric movement of bearing housing 61 causes a force to be transmitted directly to the base plate 11 which in turn is moved through an orbital path.

If desired, a suitable vibration damping means may be employed in connection with the base member 12. In one embodiment built in accordance with the present invention, the interior of the vertically disposed walls of the base member 12, as viewed in Fig. 2 of the drawings, were lined with a layer of pressed felt or the like. However, in the preferred embodiment built in accordance with the present invention, as best shown in Figs. 5 and 6 of the drawings, a small damping pad 91 is held to the interior surface of the vertical walls defining the base member 12 by a suitable damping bracket 92, which bracket was held to the base member 12 by one of the fastening means 37 which hold the motor housing 14 to the base member 12. It will be appreciated that if one touched a finger to a conventional bell, a considerable damping action would ensue, and the damping pad 91 functions in this manner.

While there has been illustrated and described what is at present believed to be a preferred embodiment of the present invention, numerous changes and modifications will readily occur to those skilled in the art, and it is intended in the appended claims to cover all those changes and modifications as fall within the true spirit and scope of the present invention.

What is claimed as new and desired to be secured by Letters Patent of the United States is:

1. A surface treating machine comprising a base member, a base plate spaced from and resiliently supported from said member, motor means including a shaft jour-

40

45

nalled in said base member, a rotatable drive member driven by said shaft and having a first recess centered relative to the periphery of said drive member and opening on at least one face of said drive member, said drive member also having a second recess eccentric relative to said first recess and opening on the opposite face of said drive member from said one face, said recesses longitudinally overlapping one another, first bearing mounting means fixed to said base member and extending into said first recess, second bearing mounting means fixed to said base plate and extending into said second recess, first elongated bearing means positioned in said first recess and mounting said rotatable member rotatably on said first bearing mounting means, and second elongated bearing means mounted in said second recess and mounting said rotatable member rotatably on said second bearing mounting means, said first bearing means and said second bearing means overlapping one another to an extent such that the center of forces transmitted from said second bearing means is between the ends of said first bearing means.

2. The surface treating machine of claim 1 wherein said base member is a rectangular boxlike member open at the bottom with said base plate supported adjacent said open end thereof, and wherein the resilient support for said base plate comprises a plurality of columns of rubberlike material disposed between said base member and base plate within said boxlike member.

3. The surface treating machine of claim 1 wherein vibration damping means are associated with said base member.

4. The combination of claim 1 wherein a counterweight is secured to said rotatable drive member to balance the unbalanced forces created by virtue of the eccentric recess, said counterweight being a mass effectively disposed along the line of effective force transmission between said second bearing mounting means and said rotatable drive member.
